UNITED STATES PATENT OFFICE

LOUIS H. PERLMAN, OF NEW YORK, N. Y.

WHEEL.

1,265,951.

Specification of Letters Patent. Patented May 14, 1918.

Application filed September 23, 1916. Serial No. 121,826.

To all whom it may concern:

Be it known that I, LOUIS H. PERLMAN, a citizen of the United States, residing at New York city, in the county of New York and State of New York, have invented certain new and useful Improvements in Wheels; and I do hereby declare the following to be a full, clear, and exact description of the invention, such as will enable others skilled in the art to which it appertains to make and use the same.

This invention relates to improvements in demountable rims of the channel type, that is the type in which flanges are formed integral with the base or main body of the rim in position to engage the beads of a tire.

The object in view is the effective locking of the ends of the rim together, the rim being cross cut to enable mounting and demounting of a tire.

With this and further objects in view, as will in part hereinafter be specified and in part become apparent, the invention comprises certain novel constructions, combinations and arrangements of parts as subsequently specified and claimed.

In the accompanying drawing,—

Figure 1 is a fragmentary plan view of a structure embodying the features of the present invention.

Fig. 2 is a transverse axial section taken on the plane indicated by line 2—2 of Fig. 1, a fragment of a wheel being shown and seen also partly in similar section.

Fig. 3 is a section taken on the plane indicated by line 3—3 of Fig. 2.

Fig. 4 is a fragmentary plan of a modified embodiment.

Referring to the drawing by numerals, 1 indicates an ordinary wheel body provided with the usual fixed rim or felly band 2 on which is mounted the demountable rim 3, the said rim being held at the inner edge by the stop flange 4 formed integral with felly band 2, and at the other edge by the usual side wedges or other similar locking devices, not illustrated.

The rim 3 is cross cut forming ends 4 and 5. The end 4 is provided with a tongue 6 extending circumferentially away from the end. The free end of the tongue 6 is formed on an incline, as clearly seen at 6', the inclination being such that one corner of the free end of the tongue is advanced circumferentially beyond the other corner.

The end portion 5 of the rim is formed with a depression 7 provided by the inward offsetting of the material of the rim, as indicated at 8. The offset material 8 is shaped to conform generally to the contour of the tongue 6, and at the inner terminus of the offset portion 8 the material of the rim is cut away to form an aperture 9. The tongue 6 is provided with an inward projection 10 at its free end which projection extends through the aperture 9 and extends parallel to a similar projection 11 extending from the adjacent end of the depressed portion 8. The two projections 10 and 11 are adapted to extend into a recess 12 in the felly band 3 for serving as a driver.

The projections 10 and 11, as clearly indicated by dotted lines in Fig. 1, are disposed at the same inclination as is the free edge of the tongue 6 and, of course, the recess 12 is formed to receive the projections and is accordingly set at an inclination to the planes of the faces of the wheel. The direction of the incline in each instance is such as to tend to wedge the rim 3 axially toward the flange 4. The actual direction of the inclination will depend upon whether the wheel 2 is a driver or one of the steering wheels, and the rim 2 will be positioned on the respective wheel accordingly.

The operation of the structure is believed to be obvious. The rim, of course, is rocked onto and off of the wheel as is usual with any ordinary demountable rim. When it is desired to interchange tires, the end 5 is depressed far enough to cause the rim flanges to pass beneath the tire beads; which will be far enough to cause the projection 10 to escape through the recess 9. Thereupon the end 5 may be either pressed axially away from the rim and the tire removed with an unthreading movement, or the end 5 may be forced by suitable apparatus to move within and to a lapping position relative to the end portion 4 until the diameter of the rim 3 has sufficiently diminished to enable the tire to be lifted off of the rim, or the rim withdrawn from the tire. The application of the tire will merely require a converse movement.

In Fig. 4 is seen a slightly modified embodiment consisting in having the cross-cut of the rim inclined so that one end of the cut is advanced circumferentially relative to the other, and the cut is preferably disposed at an angle corresponding to the angle of

the slot 9^a. Thus the cross-cut and slot extend in parallel planes. The advantage of this arrangement resides in the fact that the width of the depressed portion beneath the tongue 6^a is uniform, and is, therefore, not weaker at one edge than at the other.

What I claim is:—

1. In a wheel structure, a demountable rim of the channel type having a cross cut providing end portions, one of the end portions being formed with an outstanding tongue, and the other end portion with a depression adapted to receive the tongue, the tongue having its outer end formed on an oblique line so that one edge of the tongue is longer in a circumferential direction than the other, and means for preventing separation of the ends.

2. In a wheel structure, a demountable rim of the channel type having a cross cut providing end portions, one of the end portions being formed with an outstanding tongue, and the other end portion with a depression adapted to receive the tongue, the tongue having its outer end formed on an oblique line, so that one edge of the tongue is longer in a circumferential direction than the other, and means projecting from the oblique end of the tongue into engagement with the rim for locking the ends of the rim against separation.

3. In a wheel structure, a demountable rim of the channel type having a cross cut providing end portions, one of the end portions being formed with an outstanding tongue, and the other end portion with a depression adapted to receive the tongue, the tongue having its outer end formed on an oblique line, so that one end of the tongue is longer in a circumferential direction than the other, and a projection extending from the oblique end of the tongue through the end portion of the rim engaged by the tongue.

4. In a wheel structure, a demountable rim of the channel type having a cross cut providing end portions, one of the end portions

being formed with an outstanding tongue, and the other end portion with a depression adapted to receive the tongue, the tongue having its outer end formed on an oblique line, and a projection extending from the oblique end of the tongue through the end portion of the rim engaged by the tongue, the projection lying also on an incline corresponding to that of the end of the tongue and extending inward a distance sufficient for serving as a driver.

5. In a wheel structure, a demountable rim of the channel type having a cross cut providing end portions, one of the end portions being formed with an outstanding tongue, and the other end portion with a depression adapted to receive the tongue, the tongue having its outer end formed on an oblique line, and a projection extending from the oblique end of the tongue through the end portion of the rim engaged by the tongue, the projection extending a sufficient distance inwardly to serve as a driver.

6. In a wheel structure, the combination with a wheel body having a recess, of a demountable rim therefor of the channel type having a cross cut providing the rim with end portions, one end portion being formed with a tongue outstanding toward and adapted to lap a part of the other end portion, the second end portion being formed with a depression adapted to receive the tongue, the tongue being formed with an inclined free end oblique to the faces of the wheel body so that one edge of the tongue is longer in a circumferential direction than the other, and a projection extending along the oblique end of the tongue into engagement with the recess in the wheel body for serving as a driver.

In testimony whereof I affix my signature in presence of two witnesses.

LOUIS H. PERLMAN.
